SEWING MACHINE THREAD RATIO CONTROL

Martin L. Cook, Western Springs, Ill., assignor to Union Special Machine Company, Chicago, Ill., a corporation of Illinois

Application May 7, 1952, Serial No. 286,510

14 Claims. (Cl. 112—242)

The present invention relates to sewing machines and more particularly to thread control mechanisms for use with sewing machines having thread carrying stitch forming instrumentalities.

In sewing machines having a plurality of stitch forming instrumentalities, it is desirable to provide means for insuring uniform delivery of the thread or threads at a predetermined rate or rates to the various stitch forming instrumentalities. Uniform thread delivery is necessary for the formation of uniform stitches. Various means for improving uniformity of thread delivery have been suggested heretofore but such means have only partially solved the problems involved. For example, in U. S. Patent 2,332,932, issued July 30, 1940, on an invention of Albert S. Riviere, there is disclosed a sewing machine having thread controlling means that is driven by pull on one or more of the threads incident to consumption of the thread during stitch formation. Rotation of the wheel serves to deliver the threads in fixed ratios.

Such prior thread control means, however, do not completely overcome the difficulties of uniform stitch formation. For instance, in the use of these prior thread controls, inertia effects tend to cause tight stitches or thread breakage when the machine is started or the speed thereof is increased. On the other hand, when the machine is slowed or stopped, overthrow tends to cause loose stitch formation and sometimes skipping.

The principal object of the present invention has been to provide an improved thread control mechanism, for use with sewing machines having a plurality of stitch forming instrumentalities for carrying one or more threads, which will insure the production of uniform stitches under all conditions of operation.

A further object of the invention has been to provide an improved thread control mechanism of the above type in which thread metering is independent of the thickness of the work being sewn.

Another object of the invention has been to provide an improved thread control mechanism of the above type in which thread delivery to the stitch forming devices is independent of variations in thread conditions between the thread supply source and the control mechanism.

A feature of the invention has been to provide an improved thread control mechanism which is driven from the operating mechanism of the machine and is adapted to deliver predetermined amounts of thread to the stitch forming devices on each cycle of operation of the machine. This eliminates the need of a clutch or like device to suppress backlash of the control means.

Other and further objects and features of the invention will appear from the following description.

In accordance with the invention, a sewing machine having stitch forming and work feeding instrumentalities and driving connections therefor is provided with control means for delivering one or more threads to the stitch forming instrumentalities, the control means being positively driven by the driving connections to insure the

2

production of uniform stitches. The control means comprises a rotatable member or members affording one or more generally circular thread carrying surfaces with each of which a respective one of the threads may have peripheral contact for positive control thereof en route to the respective stitch forming instrumentality and a driving mechanism intercoupling a driven part of the sewing machine, such as one of the driving connections mentioned, with the rotatable member or members to rotate the latter. The arrangement is such that the thread or threads will be delivered by the control means to the stitch forming instrumentalities at the desired rate or rates. In the case of a plurality of threads, the relative peripheral velocities of the thread engaging surfaces of the rotatable member or members are proportional to the desired ratios.

The invention will now be described in greater detail with reference to the appended drawings wherein like reference characters have been used to denote like elements and in which:

Fig. 1 is a top plan view of a cup feed sewing machine having a thread control mechanism according to the invention and having the machine cover plate removed to afford a view of the driving mechanism;

Fig. 2 is a side elevational view, partly in section, of the sewing machine of Fig. 1;

Fig. 3 is a front elevational view, partly in section, of the sewing machine of Fig. 1;

Fig. 4 is an exploded view of the thread ratio control devices shown in Figs. 1, 2 and 3;

Fig. 5 is a fragmentary sectional view illustrating a modification of the thread ratio control devices shown in Fig. 3 and the associated portion of the sewing machine frame; and

Fig. 6 is a side elevational view of the apparatus shown in Fig. 5.

Referring now to the drawings and more particularly to Figs. 1, 2 and 3, the thread ratio control mechanism has been illustrated in connection with a three thread cup feed sewing machine of known type, substantially as disclosed in U. S. Patents Nos. 2,043,748 and 2,043,749, issued June 9, 1936, to H. Hacklander. The invention is not, of course, limited to cup feed sewing machines or three thread sewing machines, but is adaptable to many types of sewing machines employing a plurality of stitch forming instrumentalities carrying one or more threads.

The sewing machine illustrated is provided with a frame 10 having a main shaft 11 journaled in projections 12 and 13 provided in either side of the frame 10. Shaft 11, which actuates all of the stitch forming instrumentalities and the work feeding and thread supplying mechanisms of the machine, extends beyond the projections 12 and 13 and carries at its ends combined hand and belt wheels 14 and 15.

Feeding of the work is accomplished by tangentially-opposed, intermittently rotated vertical axis feeding wheels or cups 16 and 17 which intermittently advance, between them, a plurality of superposed fabric edges for presentation to the stitch forming instrumentalities of the machine. These instrumentalities include a needle 18 and a pair of loopers 19 and 20 for manipulating their respective threads in known manner to produce an overedge seam along the fabric edges as they are advanced by the feed cups. The needle 18 is secured to an endwise reciprocating needle bar 21. The looper 19 is secured to an oscillating shaft 22 which is inclined at a small angle to the horizontal, while the overedge looper 20 is secured to a similarly inclined shaft 23 which is reciprocated endwise as well as oscillated about its axis. The shafts 21, 22 and 23 derive their movements in properly timed relation through actuating mecha-

nisms driven by eccentrics or cranks on the main shaft 11, in known manner.

A rock member 30 (Fig. 3) carried on a horizontal shaft 31 is provided with a lower arm 32 pivotally connected to a pitman by means of a strap 33 on the latter and a pin 34 carried by the arm. The pitman is provided with another strap 35 connected to an eccentric secured to the shaft 11. Rock member 30 is also provided with a slotted upper arm 36 which carries a pin 37 by means of which the arm is pivotally connected to one end of a connecting rod 38. The other end of connecting rod 38 (Figs. 1 and 2) is connected to the operating arm 39a of a one-way clutch 39 through a ball and strap connection 40. Clutch 39, which may be of the type disclosed in U. S. Patent No. 2,398,652, issued to H. J. Le Vesconte on April 16, 1946, serves to transmit intermittent motion from rock member 30 to a rear feed cup shaft 41. Shaft 41, which is journaled in a depending portion 42 (Fig. 2) of frame 10, carries at its lower end the rear or inner feed cup 16. The extent of movement of the feed cup on each revolution of shaft 11 may be varied to provide the desired stitch length by adjusting the pin 37 along the slot (not shown) in the arm 36.

Mounted at the top of the rear feed cup shaft 41 is 25 a gear 43 which is arranged to mesh with a gear 44 secured to the upper end of a front or outer feed cup shaft 45. This shaft is formed in two parts. The front feed cup 17 is mounted on the lower end of the lower part of shaft 45 so that feed cups 16 and 17 are driven synchronously in opposite directions by meshing gears 43 and 44. The lower portion of front feed cup shaft 45 is journaled in a sleeve 46 carried by a bracket 47 pivotally mounted on an overhanging portion 48 of the frame 10 by a rock shaft 49 (Fig. 2). Upper portion of shaft 45 is journaled in a bushing 50 carried by the frame, the two portions of shaft 45 being connected by means of a universal coupling 51—52. This permits the lower portion of the shaft to be swung outwardly by the rocking of the bracket 47. Suitable means, not shown in the drawings but which may be of the type shown in U. S. Patent 2,448,774, issued September 7, 1948, to M. L. Cook, may be provided to urge the cup 17 yielding into engagement with the cup 16 and to swing the cup 17 outwardly to a limited extent away from cup 16 to enable the introduction of work between the cups.

A vertical shaft 55 is carried by a bracket 56 mounted on frame 10 by screws 57 and 58 (Fig. 1). A gear 59, which is preferably smaller than gears 43 and 44, is mounted on the upper end of shaft 55 and arranged to mesh with the gear 43. A bevel gear 60 is secured to the lower end of shaft 55 and is arranged to mesh with a bevel gear 61 secured to the inner end of a horizontal shaft 62. The other end of shaft 62 extends outside the machine frame 10. Shaft 62 is supported in part by a bracket 63 (Figs. 1 and 3) affixed to the inside of frame 10 by means of screws 64 and is further supported by a bushing, to be hereinafter described, carried by the wall of the frame. The shaft 62 drives a thread ratio control unit 65.

As shown in Figs. 1 through 4, the thread ratio control unit 65 comprises a single multi-grooved wheel 66 which is carried on that portion of shaft 62 external to the machine frame 10. Wheel 66 is provided with three grooves 67, 68 and 69. Grooves 67 and 68, which receive the respective looper threads, are, in the illustrated embodiment, of equal diameters. Groove 69, which receives the needle thread, is of a slightly smaller diameter because, in a sewing machine of the type illustrated adapted particularly for the seaming of hosiery, a smaller amount of needle thread than looper thread per stitch is required. It is evident that wheel 66 may be provided with a number of grooves equal to the number of threads to be metered and that the relative groove diameters

may be arranged to deliver the respective threads in the desired ratios.

At the outer end of shaft 62 there is provided a releasable means, generally designated 70, for maintaining the wheel 66 in frictional driving contact with a clutch or driving disc 71. The releasable means 70 comprises a screw 72 and a nut 73 against which one end of a compression spring 74 (Fig. 4) bears. At its other end the spring 74 bears against the bottom of a recessed portion 75 of a knurled collar 76. The collar 76 is slidably mounted on shaft 62 and is arranged to be pressed against the wheel 66 by spring 74 to force wheel 66 into frictional driving engagement with the clutch disc 71. Clutch disc 71 is fixed to shaft 62 by set screws 77.

The knurled collar 76 is provided with a notch 80 which is adapted to receive a pin 81 extending radially from shaft 62, the depth of the notch being sufficient to permit free axial movement of the collar to the extent required to urge the wheel 66 into engagement with the disc 71 when the notch is aligned with pin 81. When it is desired to release the spring pressure from wheel 66, thereby to disengage wheel 66 from clutch disc 71, the collar 76 may be pulled toward the outer end of shaft 62 until the notch 80 clears the pin 81. The collar 76 is then rotated in either direction so that its inner end bears against pin 81 rather than the wheel 66. In order positively to disengage clutch disc 71 and wheel 66, so that wheel 66 may freely rotate on shaft 62, a light spring 82 may be fitted around the shaft 62 between clutch disc 71 and wheel 66. Slight recesses may be provided in one or both of the disc 71 and wheel 66 to accommodate spring 82. Uncoupling of the wheel 66 from the disc 71, in the manner explained, facilitates the threading of the needle and loopers.

A flanged bushing 85, threaded at each end, fits into a hole 86 (Fig. 4) in the side of the overhanging portion 48 of the frame 10 to give additional bearing to the shaft 62 and also to provide support for a thread guide and tension disc bracket 87. A flange 88 of bushing 85 fits tightly against the outside of overhanging portion 48. A washer 89 and a nut 90 are provided over the threaded end of bushing 85 on the inside of the machine frame. The washer 89 provides an oil seal and the lock nut 90 securely fastens bushing 85 to the machine frame.

The thread guide and tension disc bracket 87 is provided with a generally central flat portion 91 (Fig. 4) having a hole 92 adapted to fit over the outer end of bushing 85 and around the flange 88. A lock washer 93 and a nut 94 rigidly secure the bracket 87 to the frame. A small recess or well 95 (Fig. 3) is provided in overhanging portion 48 to receive a pin 96 projecting inwardly from bracket 87 to align and prevent rotation of bracket 87. Bracket 87 is provided with two sets of thread guiding eyelets. One set comprises eyelets 97, 98 and 99 each arranged to direct a respective thread from its associated groove in wheel 66 to its associated stitch forming element. It will be understood that other thread guides may be provided between the eyelets mentioned and the eyes of the needle and loopers. Eyelets 100, 101 and 102, comprising the other set carried by bracket 87, are arranged to direct the respective threads from associated tension discs 103, 104 and 105 to the respective grooves of wheel 66. Tension discs 103, 104 and 105 are mounted on a sleeve 106 secured to bracket 87 by means of nuts 107 and 108 disposed on opposite sides of a hole 109 in bracket 87.

Thread tension between the thread supply and the control wheel may be adjusted suitably by varying the pressure provided by a spring 110 acting between a spacer 103' and a knurled nut 111 threaded on the end of sleeve 106. Spacers 104' and 105' are provided between discs 103 and 104 and 105, respectively.

Each thread may be wound around wheel 66 in its respective groove one or more times as desired. It is desirable to wrap the threads around the wheel a suf-

ficient number of turns to prevent slippage in relation to the wheel. The number of turns required for this purpose will depend upon the tension applied to each thread as the threads are pulled up in the stitches. The thread tension discs may, if desired, be replaced with guide eyelets since the tension discs have no effect on thread tension at the stitch forming instrumentalities.

Since the shaft 62 is driven through gears 43, 59, 60 and 61 from the rear feed cup shaft 45, any changes in speed of the machine or in stitch length will be reflected in the speed of rotation of shaft 62. Furthermore, since the control wheel 66 rotates with the shaft 62, such changes will directly affect the amounts of the respective threads metered by the wheel 66. It is evident, therefore, that metering of the proper amounts of the respective threads will be automatically adjusted to compensate for any changes in speed or stitch length. Metering of the threads in the proper relative ratios is, of course, ensured by causing the threads to pass around the associated grooves of the control wheel 66, the rate of delivery of each thread being determined by the peripheral speed of the surface of the engaged groove.

A unitary control wheel 66, as described above, may be replaced with a plurality of separate wheels 66A, 66B and 66C, as illustrated in Fig. 5. The unitary construction is simpler, easier to assemble and costs less. The separate construction, on the other hand, has the advantages of being easier to thread and of providing variable thread ratios through replacing one of the metering elements rather than the entire wheel.

Referring now to Figs. 5 and 6, the shaft 62 has mounted thereon three control wheels 66A, 66B and 66C, provided with grooves 67', 68' and 69', respectively, for receiving the looper and needle threads. The wheel diameters in the groove portions thereof may be selected to provide the desired thread ratios. The wheels 66A, 66B and 66C are maintained in frictional driving relationship with each other and with the driving clutch disc 71' by use of a spring and collar arrangement identical to the one described hereinbefore in connection with the unitary control wheel 66 and forming a releasable means designated generally as 70'. Releasable means 70' comprises a screw 72', a nut 73', a spring 74' and a collar 76' having a recessed portion 75'. The mounting provided for shaft 62 is somewhat simpler than the one previously described and comprises a bushing 85' pressed into a hole 86' in the machine frame. A bracket 87' carrying the thread tension discs and the thread guiding eyelets is mounted directly on the machine frame by means of screws 120. The tension discs and thread guiding eyelets of Figs. 5 and 6 correspond to the like elements of Figs. 1-4.

When the releasable means 70' is pulled out, the control wheels 66A, 66B and 66C are freely rotatable individually on shaft 62, which facilitates threading thereof. Member 76' may be held in released position by disengaging its notch 80' from the pin 81' and turning it slightly to cause its inner surface to engage the pin.

The size of the control wheels in either the unitary or separate construction is inversely proportional to the gear ratio between the primary driving gear and the ultimately driven gear, i. e., between gears 43 and 61. With the usual standard stitch length of 17 or 18 stitches per inch, approximately six inches of needle thread and seven inches of each looper thread go into each two inch length of seam. It is evident, therefore, that if the thread groove diameters are smaller than the diameter of the feed cup, which will almost invariably be the case, a gear ratio of more than 3:1 will be required. For example, a gear ratio of 5:1 with a needle thread groove diameter of 1.17" and looper thread groove diameters of 1.36" will provide normal proportionate delivery of thread when feed cups of the conventional diameter, i. e., 1.95" are used.

While the invention has been described in relation to

specific embodiments thereof and for a specific use, it should be understood that it is not limited thereto for obvious modifications thereof will occur to those skilled in the art without departing from the spirit and scope of the invention as set forth in the appended claims.

What is claimed is:

1. A sewing machine, comprising a rotary shaft, a plurality of stitch forming and work feeding instrumentalities, driving connections therefor from said shaft for operating said stitch forming and work feeding instrumentalities, said connections including an intermittently operable part and a control mechanism for delivering thread to said stitch forming instrumentalities for producing uniform stitches, said mechanism comprising rotatable means affording at least one generally circular thread carrying surface with which said thread may have peripheral contact for positive control thereof en route to the stitch forming instrumentalities, and means intercoupling said intermittently operable part of said driving connections and said rotatable means to rotate the latter, said means being arranged to impart a desired peripheral velocity to said thread carrying surface.

2. A sewing machine, comprising a rotary shaft, a plurality of stitch forming and work feeding instrumentalities, driving connections from said shaft for operating said work feeding instrumentalities, said driving connections being adjustable to vary the extent of feed movement of said work feeding instrumentalities upon each revolution of said shaft, and a control mechanism for delivering a plurality of threads to said stitch forming instrumentalities in desired ratios and at desired rates for producing uniform stitches, said mechanism comprising rotatable means affording a plurality of generally circular thread carrying surfaces with each of which a respective one of said threads may have peripheral contact for positive control thereof en route to the respective stitch forming instrumentalities, and means intercoupling said driving connections and said rotatable means to rotate the latter to an extent related to said feed movement of the work feeding instrumentalities, said means being arranged to impart peripheral velocities to said thread carrying surfaces corresponding to the desired rates of delivery of the threads carried thereby.

3. A sewing machine, comprising a rotary shaft, a plurality of stitch forming and work feeding instrumentalities, driving connections from said shaft for operating said work feeding instrumentalities, said driving connections being adjustable to vary the extent of feed movement of said work feeding instrumentalities upon each revolution of said shaft, and a control mechanism for delivering a plurality of threads to said stitch forming instrumentalities in desired ratios and at desired rates for producing uniform stitches, said mechanism comprising a rotatable member having a plurality of generally circular thread carrying surfaces with each of which a respective one of said threads may have peripheral contact for positive control thereof en route to the respective stitch forming instrumentalities, the relative diameters of said surfaces being proportional to said desired ratios, and driving means intercoupling said driving connections and said rotatable member to rotate the latter at a rate related to said feed movement of the work feeding instrumentalities and at which said threads will be delivered from said surfaces to said stitch forming instrumentalities at said desired rates.

4. A sewing machine, comprising a plurality of stitch forming and work feeding instrumentalities, a rotary drive shaft, driving connections from said shaft for operating said work feeding instrumentalities, and a control mechanism for delivering a plurality of threads to said stitch forming instrumentalities in desired ratios and at desired rates for producing uniform stitches, said mechanism comprising a rotatable member having a plurality of generally circular thread carrying surfaces with each of which a respective one of said threads may have peripheral con-

tact for positive control thereof en route to the respective stitch forming instrumentalities, the relative diameters of said surfaces being proportional to said desired ratios, and driving means intercoupling said feeding instrumentalities and said rotatable member to rotate the latter at a variable angular speed in relation to the angular speed of said shaft to cause said threads to be delivered from said surfaces to said stitch forming instrumentalities at said desired rates.

5. A sewing machine, comprising a plurality of stitch forming and work feeding instrumentalities and driving connections therefor, said driving connections for said work feeding instrumentalities being adjustable to vary the extent of feed movement imparted during each cycle of the machine, and a control mechanism for delivering a plurality of threads to said stitch forming instrumentalities in desired ratios and at desired rates for producing uniform stitches, said mechanism comprising a plurality of rotatable generally annular thread carrying members with each of which a respective one of said threads may have peripheral contact for positive control thereof en route to the respective stitch forming instrumentalities, the relative outer diameters of said members being proportional to said desired ratios, and means intercoupling said feeding instrumentalities and said thread carrying members to rotate the latter at a rate related to said feed movements and at which said threads will be delivered from said members to said stitch forming instrumentalities at said desired rates.

6. A sewing machine, comprising a rotary shaft, a plurality of stitch forming and work feeding instrumentalities, driving connections from said shaft for operating said work feeding instrumentalities, said connections being adjustable to vary the extent of operation of said work feeding instrumentalities upon each revolution of said shaft, and a control mechanism for delivering a plurality of threads to said stitch forming instrumentalities in desired ratios and at desired rates for producing uniform stitches, said mechanism comprising a plurality of rotatable generally annular thread carrying members with each of which a respective one of said threads may have peripheral contact for positive control thereof en route to the respective stitch forming instrumentalities, the relative outer diameters of said members being proportional to said desired ratios, and a driving mechanism intercoupling said driving connections and said thread carrying members to rotate the latter at a rate related to said extent of operation of said work feeding instrumentalities and at which said threads will be delivered from said members to said stitch forming instrumentalities at said desired rates.

7. A sewing machine, comprising a rotary shaft, a plurality of stitch forming and work feeding instrumentalities, driving connections from said shaft for operating said work feeding instrumentalities, said connections being adjustable to vary the extent of operation of said work feeding instrumentalities upon each revolution of said shaft, and a control mechanism for delivering a plurality of threads to said stitch forming instrumentalities in desired ratios and at desired rates for producing uniform stitches, said mechanism comprising a shaft connected to said driving connections for rotation thereof to extents proportional to the extents of feed of said work feeding instrumentalities, and thread carrying means mounted on said shaft for rotation therewith, said thread carrying means affording a plurality of generally circular thread carrying surfaces with each of which a respective one of said threads may have peripheral contact for positive control thereof en route to the respective stitch forming instrumentalities, the relative diameters of said surfaces being proportional to said desired ratios.

8. A sewing machine, comprising a rotary shaft, a plurality of stitch forming and work feeding instrumentalities, driving connections from said shaft for operating said work feeding instrumentalities, said connections being

adjustable to vary the extent of operation of said work feeding instrumentalities upon each revolution of said shaft, and a control mechanism for delivering a plurality of threads to said stitch forming instrumentalities in desired ratios and at desired rates for producing uniform stitches, said mechanism comprising a shaft connected to said driving connections for rotation thereof to extents proportional to the extents of feed of said work feeding instrumentalities, a thread carrying member mounted on said shaft and being rotatable thereon, said thread carrying member affording a plurality of generally circular thread carrying surfaces with each of which a respective one of said threads may have peripheral contact for positive control thereof en route to the respective stitch forming instrumentalities, the relative diameters of said surfaces being proportional to said desired ratios, a clutch element mounted on said shaft for rotation therewith, and releasable means for urging said member into frictional driving engagement with said clutch element.

9. A sewing machine, comprising a rotary shaft, a plurality of stitch forming and work feeding instrumentalities, driving connections from said shaft for operating said work feeding instrumentalities, said connections being adjustable to vary the extent of operation of said work feeding instrumentalities upon each revolution of said shaft, and a control mechanism for delivering a plurality of threads to said stitch forming instrumentalities in desired ratios and at desired rates for producing uniform stitches, said mechanism comprising a shaft connected to said driving connections for rotation thereof to extents proportional to the extents of feed of said work feeding instrumentalities, a plurality of generally annular thread carrying members mounted on said shaft and being rotatable thereon, each of said thread carrying members affording a generally circular thread carrying surface with which a respective one of said threads may have peripheral contact for positive control thereof en route to the respective stitch forming instrumentality, the relative diameters of said surfaces being proportional to said desired ratios, a clutch element mounted on said shaft for rotation therewith, and releasable means for urging said members into frictional driving engagement with each other and with said clutch element.

10. A cup feed sewing machine, comprising a frame having a hollow lubricant retaining portion, a plurality of stitch forming instrumentalities, a pair of work advancing feed cups, a pair of feed cup shafts for rotating said feed cups, driving means for intermittently oppositely rotating said feed cup shafts, and a control mechanism for delivering a plurality of threads to said stitch forming instrumentalities in desired ratios and at desired rates for producing uniform stitches, said mechanism comprising a thread control shaft, means including a first gear mounted on one of said feed cup shafts and a second gear mounted on said thread control shaft within said hollow lubricant retaining portion of the frame for rotating said thread control shaft at a speed proportional to the operating speed of said feed cups, and thread carrying means mounted on said shaft for rotation therewith, said thread carrying means affording a plurality of generally circular thread carrying surfaces with each of which a respective one of said threads may have peripheral contact for positive control thereof en route to the respective stitch forming instrumentalities, the relative diameters of said surfaces being proportional to said desired ratios.

11. A cup feed sewing machine, comprising a frame having a hollow lubricant retaining portion, a plurality of stitch forming instrumentalities, a pair of work advancing feed cups, a pair of feed cup shafts for rotating said feed cups, driving means for intermittently oppositely rotating said feed cup shafts, and a control mechanism for delivering a plurality of threads to said stitch forming instrumentalities in desired ratios and at desired rates for producing uniform stitches, said mech-

anism comprising a thread control shaft, means including a first gear mounted on one of said feed cup shafts and a second gear mounted on said thread control shaft within said hollow lubricant retaining portion of the frame for rotating said thread control shaft at a speed proportional to the operating speed of said feed cups, thread carrying means mounted on said thread control shaft for rotation therewith, said thread carrying means affording a plurality of generally circular thread carrying surfaces with each of which a respective one of said threads may have peripheral contact for positive control thereof en route to the respective stitch forming instrumentalities, the relative diameters of said surfaces being proportional to said desired ratios, a clutch element mounted on said thread control shaft for rotation therewith, said clutch being exterior of said hollow lubricant retaining portion of said frame, and releasable means for urging said thread carrying means and said clutch element into frictional driving engagement with each other.

12. A cup feed sewing machine, comprising a plurality of stitch forming instrumentalities, a pair of work advancing feed cups, a pair of feed cup shafts for rotating said feed cups, driving means for intermittently oppositely rotating said feed cup shafts, and a control mechanism for delivering a plurality of threads to said stitch forming instrumentalities in desired ratios and at desired rates for producing uniform stitches, said mechanism comprising a thread control shaft, means including a driving gear mounted on one of said feed cup shafts and a driven gear mounted on said thread control shaft for rotating said thread control shaft at a speed proportional to the operating speed of said feed cups, thread carrying means mounted on said thread control shaft for rotation therewith, said thread carrying means affording a plurality of generally circular thread carrying surfaces with each of which a respective one of said threads may have peripheral contact for positive control thereof en route to the respective stitch forming instrumentalities, the relative diameters of said surfaces being proportional to said desired ratios, a clutch disc rigidly mounted on said thread control shaft for rotation therewith, releasable means for urging said thread carrying means and said clutch disc into frictional driv-

ing engagement with each other, and a spring mounted on said thread control shaft between said thread carrying means and said clutch disc for positively disengaging the same upon release of said releasable means.

13. A sewing machine, comprising a rotary shaft, a plurality of stitch forming and work feeding instrumentalities, driving connections from said shaft to said instrumentalities for operating the latter, said connections to said work feeding instrumentalities being adjustable to vary the extent of feed movement thereof upon each revolution of said shaft to thereby vary the length of the stitches formed, a thread control mechanism for delivering thread to said stitch forming instrumentalities, and driving means intercoupling said driving connections to said work feeding instrumentalities with said thread control mechanism for positively driving the latter at a rate related to said extent of feed movement, whereby the amount of thread delivered to said stitch forming instrumentalities varies with the length of the stitches formed.

14. A sewing machine comprising a rotary shaft, a plurality of stitch forming and work feeding instrumentalities, driving connections from said shaft to said instrumentalities for operating the latter, said driving connections to said work feeding mechanism being adjustable to vary the extent of feed movement imparted upon a revolution of said shaft, a thread control mechanism for delivering thread to said stitch forming instrumentalities, connections including a friction clutch for intercoupling a variably driven portion of said driving connections to said work feeding instrumentalities with said thread control mechanism, releasable pressure means for engaging said friction clutch, whereby said thread control mechanism may be connected with or disconnected from said driving connections to said work feeding instrumentalities, and means for positively disengaging said clutch in response to release of said releasable pressure means.
